UNITED STATES PATENT OFFICE.

ORION W. NUNN, OF DENVER, COLORADO, ASSIGNOR TO LANDIS MACHINE COMPANY,
OF ST. LOUIS, MISSOURI, A CORPORATION OF MISSOURI.

WIRE-FEEDING MECHANISM FOR STAPLING-MACHINES.

1,132,111.

Specification of Letters Patent.

Patented Mar. 16, 1915.

Original application filed January 21, 1914, Serial No. 813,443. Divided and this application filed May 16, 1914. Serial No. 838,975.

To all whom it may concern:

Be it known that I, ORION W. NUNN, a citizen of the United States, residing at the city of Denver, county of Denver, State 5 of Colorado, have invented a certain new and useful Improvement in Wire-Feeding Mechanism for Stapling-Machines, of which the following is a full, clear, and exact description, such as will enable others skilled 10 in the art to which it appertains to make and use the same, reference being had to the accompanying drawings, forming part of this specification.

Figure 1 represents the top view of an 15 embodiment of my invention. Fig. 2 represents a detail front view partly in section. Fig. 3 represents a detail side view partly in section.

My invention relates to button attaching 20 machines, and more particularly to a form of button attaching machine wherein the buttons, and the wire used for the fastening means, are fed separately to the mechanism, sections of the wire cut off and 25 formed into staples and then driven into the article to which the buttons are being attached.

More specifically, my invention relates to the form of machine illustrated and described in my copending application filed 30 January 21, 1914, Serial Number 813,443, for button stapling machine of which this application is a division.

The principal object of my present invention is to provide an improved form of 35 mechanism for handling the wire, by virtue of which a proper amount of wire is fed positively and accurately to the forming mechanism, the wire held against withdrawal 40 while a portion is being severed, or a feed of the wire prevented in case no button is in the proper position to be set.

Other and further objects of my invention will be pointed out hereinafter or will 45 be obvious.

Referring to the drawings, it will be understood that the numeral 1 indicates a suitable table or support for the machine. Upon the table are supported suitable 50 brackets 2 and 4 in which is journaled a shaft 5. Shaft 5 is rotated by means of a crank 6 which is actuated by a reciprocating rod 7, or other suitable means, and said

shaft operates suitable actuating mechanism including the segment 8 (see Fig. 3), which 55 operates the button feeding, staple forming, and driving mechanism.

As illustrated in Figs. 1 and 2, 9 represents a guide tube by which buttons are fed to a handling tube 10 which directs them to 60 proper position between the antennae 11 to receive the suitable wire, and to be driven. Upon shaft 5 is mounted a disk cam 12, and on the bracket 2 a bell-crank 14 having a bearing member 15 operating in the slot of 65 the disk cam in such fashion that rotation of the disk cam by shaft 5 swings the bell crank on its pivot 14^a.

Slidably mounted in suitable standards 16 is a longitudinally slidable shuttle bar 70 17, the upper portion of which is formed with the wire channel 17^a which is covered through a part of its length by a plate 13 which holds the bar in place in the standards 16. A pivotal connection 18 between 75 bell-crank 14 and shuttle bar 17, causes the former to reciprocate the latter upon the rotation of cam 12. At the forward or left-hand end of shuttle bar 17, is a friction clamping device 19, the tension of which 80 may be regulated by adjustment of screw 20. This friction clamping device preferably consists of a pair of blocks of fiber or vulcanite, and its function is to engage the wire 21 to feed it to the forming mechanism 85 on the forward movement of the shuttle bar.

The wire is carried on a spool 22 which is suitably journaled on the support 1, the relative position of the shuttle bar and the spool being such as to permit the feeding of 90 the wire from the former through the channel 17^a of the latter. The wire is fed to the cutting and forming mechanism through a channel 24 in a guide plate 25 supported on one of the supports 4, and the portions of 95 the wire which are formed into staples are severed at the inner face of said guide plate. The opposite guide plate 25' forms an abutment to measure the wire into the proper length for the staples.

Operating in proximity to the channel 24 is a detent 26, which is pivoted on the support 4, and pressed into engagement with the wire by a spring 27. The detent has teeth inclined in the direction of the wire's movement, and its form and the nature of its 105

mounting are such as to permit forward movement of the wire 21 with the forward movement of the shuttle bar 17 when the channel 24 is not obstructed. Rearward movement of the wire with shuttle bar 17, however, is prevented by detent 26 which engages it, holding it securely against a portion of support 4.

Pivoted at 28 on support 4 is a stop lever 29, which has a laterally projecting lug 29^a (see Fig. 3) between its lower end and its pivot point. This lug is pressed by a leaf spring 30 which tends to swing the lower end of lever 29 downward. Stop lever 29 has a button engaging finger 31 and a stop finger 32. The former lies in the path of buttons fed to the antennae 11, and the latter is adapted to swing downward across the channel 24 so as to close the same and prevent the movement of wire therethrough. A sliding pin 34 is seated in support 4 and its upper end co-operates with lug 29^a on lever 29. The lower end of pin 34 lies in the path of a rack-bar 35 which is actuated in the operation of the machine by means of segment 8 which is swung by shaft 5. Rack-bar 35 has its lower end beveled off to form a cam face. Upon the downward stroke of rack bar 35, this cam face engages sliding pin 34 and pushes it upward, thereby raising the lower end of lever 29. This releases the button held under button engaging finger 31, permitting it to be carried forward by the forming and setting mechanism. Until the end of the return movement of rack bar 35, lever 29 is thus held elevated, permitting a new button to be fed to position between the antennae 11. If no button has been fed to such position, lever 29 having nothing to stop it, will swing downward to the full extent of its movement, which will interpose stop finger 32 in front of the channel 24. Consequently, upon the subsequent forward movement of shuttle bar 17, the wire will not be fed into the path of the cutting and forming mechanism, and therefore, no staple will be formed and driven at that operation of the machine. This prevents waste of wire and time, and injury to the material by uselessly driving staples without buttons.

It will be understood, of course, that, in case a button is in position to be engaged by finger 31, lever 29 will be held partially elevated thereby, so that finger 32 will not drop down to close the channel 24.

From the foregoing, it will be seen that the mechanism forms a very simple, strong and efficient wire feeding mechanism which feeds the proper amount of wire to the machine for each operation. Kinking or bending of the wire on the rearward stroke of the shuttle bar 17 is prevented by virtue of the fact that the forward end of the wire is engaged by the detent 26 in front of rather

than behind the friction clamp 19. It is also evident that the mechanism provides a wire feeding device wherein feeding of the wire is prevented unless a button is in position to be driven.

While I have shown one embodiment of my invention for the purpose of disclosure, I am aware that changes and modifications therein may be made without departing from the spirit of the invention. Therefore, it is not my intention that my invention be construed as limited to the specific form illustrated and described.

What I claim is:

1. In a button stapling machine, a wire feeding mechanism comprising a holder for wire, a shuttle bar, a tension device carried by said shuttle bar and having constant frictional engagement with the wire, and a detent operating adjacent the forward end of the wire adapted to permit the movement of wire in one direction and hold it against movement in the opposite direction by engagement superior to the engagement of the tension device.

2. In a button stapling machine, a wire feeding mechanism comprising a support for wire, a reciprocating tension device having constant frictional engagement with the wire to feed it, and a detent operating adjacent the forward end of the wire and operable by movement of wire in engagement therewith to permit movement of said wire in one direction by said tension device but prevent its movement in the opposite direction.

3. In a button stapling machine, a wire feeding mechanism comprising a support for wire, a reciprocating tension member constantly in frictional engagement with the wire, and a detent operating adjacent the forward end of the wire and operable thereby and adapted to engage the wire to overcome the frictional engagement of the tension member.

4. In a button stapling machine, a wire feeding mechanism comprising a reciprocating tension device adapted to remain constantly in frictional engagement with the wire, a detent operating adjacent the forward end of the wire and operable thereby to prevent backward movement of the wire, and a stop device adapted to co-operate with the forward end of the wire to prevent forward movement thereof.

5. In a button stapling machine, in combination, a reciprocating wire feeding tension device, a stop device, and means for interposing said stop device in the path of a wire engaged by said tension device.

6. In a machine of the class described, a spool for holding wire, a rotary shaft, a disk cam operated thereby, a shuttle member provided with a tension device adapted to engage and feed wire from said spool, and

a bell-crank operated from said cam and having pivotal connection with said shuttle member to reciprocate the same.

7. In a machine of the class described, a shuttle member having a slotted portion adapted to receive and guide a wire, a tension device mounted on the forward end of said shuttle member and adapted to engage a wire in said slotted portion, and means for reciprocating the shuttle member, for the purpose described.

8. A wire feeding mechanism comprising a support for wire, a reciprocating feeding member engaging the wire and movable thereon in both directions, and a stop member for controlling the feed of the wire

irrespective of the reciprocation of the feeding member.

9. A wire feeding mechanism comprising a support for wire, a reciprocating feeding member adapted to feed the wire intermittently, and a stop member adapted to prevent feed of the wire during a feeding movement of the feeding device.

In testimony whereof I hereunto affix my signature in the presence of two witnesses, this 11th day of May, 1914.

ORION W. NUNN.
